HEEL-SEAT FITTING MACHINE

George Hazelton, Leicester, England, assignor to
United Shoe Machinery Corporation, Borough
of Flemington, N. J., a corporation of New
Jersey

Application July 11, 1938, Serial No. 218,655
In Great Britain July 27, 1937

9 Claims. (Cl. 12—31.5)

This invention relates to the manufacture of shoes and is illustrated as embodied in a heel-seat fitting machine of the general type disclosed in United States Letters Patent No. 1,850,149, granted March 22, 1932 on an application filed in the name of Hazelton.

It is an object of the present invention to provide an improved heel-seat fitting machine for varying the widths of heel-seat tabs formed upon the soles of shoes in accordance with the widths of heels to be attached to the shoes.

With the above object in view, and in accordance with a feature of this invention, the illustrated machine is provided with means for positioning a shoe having an attached sole, a pair of sliding beds each provided with a guideway extending lengthwise of the positioned shoe, means for moving the sliding beds inward in rectilinear paths from opposite sides of the shoe, knives movable in predetermined paths controlled by said guideways for reducing the heel-seat portion of the sole, a gage having a movable abutment for measuring a heel widthwise, and means for limiting inward movement of the sliding beds in accordance with the position of said movable abutment in order to vary the paths of movement of the knives and therefore the width of the heel-seat tab formed on the sole.

The various features of the invention will be understood and appreciated from the following detailed description read in connection with the accompanying drawings, in which

Fig. 1 is a plan view, partly broken away, of the illustrated machine;

Figs. 2 and 3 are vertical sections, partly broken away, on lines II—II and III—III, respectively, of Fig. 1;

Fig. 4 is an enlarged view, partly broken away, on line IV—IV of Fig. 1;

Fig. 5 is a perspective view showing portions of the heel-seat reducing mechanism in detail;

Fig. 6 is a perspective view of portions of mechanism for limiting inward movement of the sliding beds of the machine; and

Fig. 7 is a perspective view of the heel end of a shoe the heel-seat portion of the sole of which has been reduced by the above machine.

The illustrated machine is described with reference to reducing the heel-seat portion 20 (Figs. 2 and 7) of the sole 22 of the shoe 24 and forming heel-breast receiving shoulders 26 (Fig. 2) on the sole thereby forming a tab 28 for receiving a Cuban heel 30. The shoe off the last is placed upon a jack 32 (Figs. 1 and 2) which is moved rearward along a guideway 34 (Fig. 1)

of the machine frame 36 until the rear end of the shoe engages a back gage 38 (Fig. 2), crease plates 40 (Figs. 1 and 5) being positioned between the lateral margins of the heel-seat portion 20 of the sole and the overlasted counter portion 42 (Fig. 7) of the shoe upper as the shoe is moved rearward in the machine. After the shoe has been positioned lengthwise the operator depresses a treadle (not shown) first to move the crease plates 40 inward toward each other until they are stopped by suitable mechanism which will be described later, and then to raise the jack 32 thereby forcing the shoe bottom against the undersides of the crease plates. A one-revolution clutch (not shown) is then tripped to move a pair of knives 44 (Figs. 1, 2 and 5) inward from opposite sides of the shoe to form the heel-breast receiving shoulders 26 (Fig. 7) and then to move forward a pair of knives 46 (Figs. 1, 2 and 5) to reduce the heel-seat portion of the sole by beveling cuts 48 (Fig. 7).

The crease plates 40 are secured by screws 50 (Figs. 1 and 2) to sliding beds 52 which are movable transversely on guides 54 of the main frame and have raised overhanging portions 56 (Figs. 2 and 3) provided with guideways 58 (Figs. 3 and 5) for carriers 59 to which the respective heel-seat reducing knives 46 are secured by screws 60 (Fig. 2). It will be noted (Fig. 5) that the outer margins of the heel-seat reducing knives 46 move along grooves 62 formed at the inner edges of the respective crease plates 40.

The shoulder-forming knives 44 which are secured to carriers 64 (Figs. 1 and 2) by screws 66 threaded into T-shaped blocks 68 fitting in guideways of the carrier 64, are moved inward from opposite sides of the sole through mechanism which will now be described. Each of the carriers 64 is secured by a screw 70 (Figs. 1 and 2) to a slide 72 (Fig. 1) movable along a guide 74 (Figs. 1 and 2). Screws 76 (Fig. 1) which are secured to the slides 72 by nuts 78 extend through elongated slots 80 in the guides 74 and carry at their lower ends anti-friction rolls 82 (Fig. 1) fitting in guideways 84 of sliding blocks 86. The blocks 86 are operated along guideways 88 in the sliding beds 52 by offset bellcrank levers 90 (Figs. 1, 2 and 3) journaled upon pins 92 which are secured by screws 94 (Figs. 2 and 3) to bosses 95 extending downward from the sliding beds. The bell-crank levers 90 are pivoted to links 96 (Figs. 1 and 2) the rear ends of which are pivoted to a slide 98 which is movable in a guideway 100 (Fig. 2) of the machine frame 55.

and carries a roll 102 fitting in a groove of a cam 104.

Pivoted to the pins 92 which are secured to the sliding beds 52 are a pair of links 106 (Figs. 2 and 3) which are pivoted to a slide 108 movable in a vertical guideway 110 (Fig. 2) of the machine frame. The lower end of the slide 108 is pivoted to the above-mentioned treadle (not shown). When the operator depresses the 10 treadle against the action of a spring 111 (Fig. 2) the sliding beds 52 are moved inward on the guides 54 until screws 112 (Figs. 1, 3, 4 and 6) which are threaded into lugs 114 secured by screws 116 to the sliding beds 52 engage stops 15 or wedge-shaped blocks 118 which, as will later be described, are movable into different adjusted positions in accordance with the width of the heel 30 in a heel-measuring gage 120 (Figs. 1, 2 and 3).

As above stated, the machine is provided with mechanism (not shown) operated through a treadle (not shown) for raising the jack 32 in order to force the shoe bottom against the undersides of the crease plates 49 after the shoe 25 has been positioned in the machine. Since said mechanism is fully disclosed in United States Letters Patent No. 1,840,030, granted January 5, 1932 on an application filed in the name of Gouldbourn et al., no further description is believed to be necessary. As disclosed in the above-mentioned United States Letters Patent No. 1,850,149, which shows an improved machine of the general type disclosed in said United States Letters Patent No. 1,840,030, the guides 74 are 30 adjustable upon their respective sliding beds 52 about vertical axes 122 (Fig. 3) passing through points which are located at the forward limits of movement of the lower ends 124 (Fig. 5) of the cutting edges 126 of the heel-seat reducing 35 knives 46, thereby enabling the operator to vary the paths of movement of the shoulder-forming knives 44 transversely of the sole in accordance with the transverse curvature of the breast of the heel to be attached to the shoe. It is desirable that the shoulder-forming knives 44 move along the front edges of the respective crease plates 49, irrespective of the angular 40 adjustment of the guides 74. Accordingly, a pair of auxiliary plates 128 (Figs. 1 and 5) which 45 constitute parts of the respective crease plates 40, are secured to the guides 74 by screws 129 (Figs. 1, 2 and 5), the knives 44 being in engagement with the front edges of the plates 128 and forming shear couples therewith.

It will be noted that the arrangement of the bell-crank levers 99 (Figs. 1, 2 and 3) and the links 96 is such that there is practically no relative movement between the slides 72 and the respective sliding beds 52 during the inward movement of the beds. The throw of the shoulder-forming knives 44 is practically constant, the arrangement being such that inward movement of the knives is reversed when the lower ends of their cutting edges 130 reach the vertical axes 50 122.

The carriers 59 (Figs. 3 and 5) to which the heel-seat reducing knives 50 are secured are provided at their rear ends with transverse grooves 132 (Fig. 2) for receiving a bar 134 (Figs. 1 and 70 2) of an operating slide 136 (Fig. 2) which is movable forward and rearward along a guideway 138 and carries a roll 140 fitting in a groove 142 of the operating cam 104.

It is preferable to form the heel-breast receiving shoulders 26 before reducing the heel-seat

portion of the sole and, accordingly, the shoulder-forming knives 44 are operated before the heel-seat reducing or beveling knives 46. It will be understood, however, that the sequence of operation of the shoulder-forming knives and the heel-seat reducing knives may be reversed. As in the machine disclosed in United States Letters Patent No. 1,850,149 the position of the heel-breast receiving shoulders 26 depends upon the position of the shoe determined by the back gage 10 33 which may be set in different adjusted positions along a guideway 144 (Fig. 2) through mechanism which will be described later, in accordance with the setting of the heel-measuring gage 120. 15

The heel-measuring gage 120 comprises a breast gage 146 (Figs. 1 and 2) and a slidable rear abutment 148 for engaging the rear end of the heel. As illustrated in Fig. 2, the breast gage 146 is arranged to engage the breast of the Cuban 20 heel 30, a narrow gage 150 which may be rendered operative by swinging the breast gage 146 to a raised inoperative position being provided for measuring Louis heels. The breast gage 146 is mounted upon a slide 152 which is moved into 25 different adjusted positions forward and rearward in a guideway 154 (Fig. 2) of a heel-supporting plate 155 secured to the machine frame. An adjusting screw 156 is journaled in the plate 155 and is threaded into the slide 152. The 30 rear abutment 148 is movable along a guideway 158 (Fig. 1) formed in a heel-centralizing slide 160 which is slidable in guideways 162 formed in the machine frame. The centralizing slide 160 is normally urged forward by a spring 164 until a 35 screw 166 (Fig. 1) carried by the slide engages the plate 155 (Fig. 2) of the heel gage. The forward end of the centralizing slide 160 is V-shaped to accommodate the rear portion of the heel.

Journaled in fixed bearings 168 (Fig. 1) is a 40 rock shaft 170 which may be operated through mechanism practically identical with that disclosed in United States Letters Patent No. 1,840,030 by a treadle rod 172. Secured to the right end (Fig. 1) of the rock shaft 170 is an 45 upstanding arm 174 carrying a pin 176 which engages in a vertical slot (not shown) of a block 178 (Fig. 2) carrying a shaft 180 to which a pinion 182 is secured. The block 178 is slidable forward and rearward along a guideway 184 of the 50 machine frame. The rear abutment 148 (Figs. 1 and 2) and a heel clamp actuator 186 (Fig. 2) which is slidable forward and rearward in a guideway 188 are provided with rack teeth 190, 192, respectively, which mesh with the pinion 182. 55

When the treadle rod 172 is depressed against the action of a spring 194 (Fig. 1) the arm 174 swings rearwardly carrying with it the block 178 and the pinion 182, causing both the rear abutment 148 and the clamp actuator 186 to be moved rearwardly. When the rear abutment 148 is retracted, that is, moved rearwardly, the heel is inserted attaching-face down upon the plate 155 of the heel gage with its breast against the breast gage 146, the centralizing member 160 being 60 moved rearwardly against the action of the spring 164 by the heel to enable the operator to position the heel in the gage. The treadle rod 172 is then allowed to rise under the action of the spring 194, causing the rear abutment 148 to 65 move forward into engagement with the rear part of the heel. A locking arrangement similar to that disclosed in United States Letters Patent No. 1,840,030 and comprising a stationary ratchet disk 198 (Fig. 1) which is engaged by a pawl 200 70 75

operatively connected to the treadle rod 172, prevents rotation of the rock shaft 170 in a direction to retract the rear abutment 148 from the position it assumes upon engagement with the heel.

5 In order to locate the back gage 38 in accordance with the position of the rear abutment 148, which position is determined by the length of the heel seat of the heel, the back gage is connected to the abutment by mechanism which will now be 10 described. The back gage 38, which is slideable forwardly and rearwardly in the guideway 144 (Fig. 2) has secured to it an upstanding post 202 fixed to the front end of a slide 204. Threaded into the rear end of the slide 204 is a post 206 which projects upward through clearance slots formed in the clamp actuator 186, the rear abutment 148, and the centralizing member 160. Threaded into the upper end of the post 206 is a 15 horizontal screw 208 (Figs. 1 and 2) the forward end of which is provided with a collar 210 fitting in a recess 212 (Fig. 1) of the rear abutment 148. Upon rotation of the screw 208 relative adjustment of the rear abutment 148 and the back gage 38 may be effected, a set screw 214 being provided 20 to insure that the screw shall be retained in its adjusted position.

The heel gage 120 is provided with side clamps or abutments 216 (Figs. 1, 2 and 3) secured by screws 218 to slides 220 (Figs. 1 and 3) movable 25 in guideways 222 (Fig. 1) of the machine frame. The inner portions of the slides 220 are pivoted to the rear ends of curved links 224 (Figs. 1, 2 and 3) the forward ends of which are pivoted to the heel clamp actuators 186. When the 30 treadle rod 172 connected to the arm 174 is depressed causing the clamp actuator 186 to be moved rearward as above described, the side abutments 216 are moved outward to provide clearance for the insertion of the heel in the heel gage. When the treadle rod 172 is released after 35 the insertion of the heel, the side abutments move inward to engage the sides of the heel and further insure that the heel shall be properly centralized. It is clear that when the rear abutment 148 is stopped by contact with the heel before the side abutments 216 have engaged the heel, the pinion roll 182 (Fig. 2) will roll upon the 40 rack teeth 190 of the rear abutment and will continue to move the clamp actuators 186 until 45 the abutments 216 have properly engaged the sides of the heel.

When the heel is positioned in the heel gage 120 as above described with its sides engaged by the side abutments 216 it will be appreciated that 50 the separation of the abutments 216 is determined by the width of the heel. In the illustrated machine the separation of the side abutments 216 is employed to control the separation between the heel-seat reducing knives 46 during their forward 55 movement thereby varying the width of the tab 28 in accordance with the width of the heel to be attached to the shoe.

Connected to the right slide 220 by a link 226 (Figs. 1, 3 and 4) is a rack-bar 228 (Figs. 1 and 4) 60 slideable in a guideway 230 of a bracket 232 secured by screws 233 (Fig. 4) to the machine frame. Journalized in bearings of the bracket 232 is a vertical shaft 234 (Figs. 1 and 4) to which is pinned a gear 236 meshing with the rack 238 of the bar 228. Fixed to the lower end of the shaft 234 is a large gear 240 (Fig. 4) meshing with a rack 242 which is movable forward and rearward in a guideway 244 (Figs. 3 and 6) of the bracket 232 and has secured to it the above-mentioned wedge-shaped block 118 which has an

inclined surface 246. It will be appreciated that when the side abutments 216 are moved, a corresponding movement is imparted through the above-described parts to the wedge block 118, and when the heel is positioned in the heel gage 120 the position of the block is determined by the right-hand side abutment 216 which is set in accordance with the width of the heel. The wedge-shaped block 118 serves as a stop for limiting the inward movement of the sliding beds 52 10 and the crease plates 40 secured to the beds. The screw 112 may be set in a predetermined position in the lug 114 of the sliding bed 52 by a lock nut 248. The inner end of the screw 112 is so positioned as to abut against the inclined surface 246 15 of the block 118, as illustrated in Fig. 6, when the sliding beds 52 have been moved inward into their operative positions.

As above described, the position of the wedge-shaped block 118 is determined by the width of the heel in the heel gage and therefore the distance which the sliding beds 52 are allowed to move inward before the screw 112 contacts the inclined surface 246, is determined by the width of the heel. The incline of the surface 246 of the block 118 is such that the sliding beds 52 are moved inward by such amount that the heel-seat reducing knives 46 carried thereby perform their cuts in the proper position on the sole to provide a tab 28 of a width corresponding to the 20 width of the heel in the heel gage. 30

When the screw 112 abuts against the inclined surface 246 of the wedge block 118 any tendency there may be for the thrust of the knife to move the block rearward is resisted since the rearward thrust on the block merely tends to cause the side abutments 216 to grip the heel more firmly between them. Since the diameter of the gear 240 is greater than that of the gear 236 a given movement of the side abutment 216 40 effects a considerably greater movement of the wedge-shaped block 118. Such an arrangement provides for the setting of the position of the block 118 with accuracy in accordance with the width of the heel and avoids the necessity of 45 making the incline of the surface 246 undesirably steep.

Having described the invention, what I claim as new and desire to secure by Letters Patent of the United States is:

1. A heel-seat fitting machine having, in combination, a gage for positioning a shoe, a pair of knives movable in predetermined paths respectively to reduce the heel-seat portion of an attached sole of the shoe, a heel gage comprising 55 a movable member for measuring a heel lengthwise, a slide for centralizing the heel in the heel gage, and an abutment for measuring the positioned heel widthwise, means for locating the shoe gage in different adjusted positions in accordance with the position of the movable member of the heel gage, and mechanism for varying the respective paths of movement of the knives in accordance with the position of said abutment of the heel gage thereby varying the width to 60 which the heel-seat portion of the sole is reduced in accordance with the width of the heel in the heel gage.

2. A heel-seat fitting machine having, in combination, means for positioning a shoe lengthwise, a heel gage, means for positioning a heel widthwise in said gage, a movable abutment for measuring the positioned heel widthwise, pairs of heel-seat reducing and shoulder-forming knives, 70 guideways for controlling movement of the re- 75

spective knives in predetermined paths, a stop operatively connected to the abutment, and means for moving the guideways for the knives into predetermined positions determined by the stop to vary the paths of movement of the knives in accordance with the width of the heel.

3. A heel-seat fitting machine having, in combination, means for positioning a shoe having an attached sole, a pair of sliding beds each provided with a guideway extending lengthwise of the positioned shoe, means for moving the sliding beds inward in rectilinear paths from opposite sides of the shoe, knives movable in predetermined paths controlled by said guideways for reducing the heel-seat portion of the sole, a gage having a movable abutment for measuring a heel widthwise, and means for limiting inward movement of the sliding beds in accordance with the position of said movable abutment in order to vary the paths of movement of the knives and therefore the size of the heel-seat tab formed on the sole.

4. A heel-seat fitting machine having, in combination, means for positioning a shoe having an attached sole, a pair of sliding beds each having a guideway extending lengthwise of the shoe, a crease plate carried by each of the sliding beds, means for moving the sliding beds inward in rectilinear paths from opposite sides of the positioned shoe, knives movable in predetermined paths controlled by said guideways for reducing the heel-seat portion of said sole, a heel gage comprising an abutment for measuring a heel widthwise, and a stop operatively connected to said abutment for limiting inward movement of the sliding beds toward each other and thereby varying the positions of said guideways in accordance with the width of the heel in the gage.

5. A heel-seat fitting machine having, in combination, an abutment for measuring a heel widthwise, means for positioning a shoe having an attached sole, a pair of sliding beds, a crease plate secured to each of the sliding beds, a pair of knives for reducing the heel-seat portion of the sole, a pair of knives for forming heel-breast receiving shoulders upon the sole, guideways formed in said sliding beds for controlling the paths of movement of corresponding pairs of heel-seat reducing and shoulder-forming knives, a stop connected to said abutment, and means for moving the sliding beds toward each other until limited by said stop preparatory to reducing the heel-seat portion of the sole.

6. A heel-seat fitting machine having, in combination, a back gage for positioning a shoe lengthwise, a heel gage comprising a stationary abutment, a slide constructed and arranged to force a heel against said abutment and to position the heel widthwise, a member for measuring the heel widthwise, crease plates, heel-seat reducing knives, guideways for the heel-seat reducing knives, mechanism for moving the crease

plates and the guideways for the knives into different adjusted positions transversely of the sole, and means connected to said member for limiting inward movement of the crease plates and the guideways in accordance with the widthwise measurement of the heel.

7. A heel-seat fitting machine having, in combination, means for positioning a shoe having an attached sole, a pair of knives for reducing the heel-seat portion of the sole, a pair of knives for forming heel-breast receiving shoulders on the sole, a pair of sliding beds, guideways in the sliding beds for controlling the paths of movement of the heel-seat reducing and the shoulder-forming knives, crease plates carried by the sliding beds, a heel gage comprising an abutment for measuring a heel widthwise, a stop, mechanism for operatively connecting the stop with said abutment to move the stop into different adjusted positions in accordance with the width of the heel in the heel gage, means for moving the sliding beds inward from opposite sides of the sole, and adjustable means carried by the sliding beds for engaging the stop to limit the inward movement of the beds in order to position the guideways for the heel-seat reducing and the shoulder-forming knives in predetermined positions in accordance with the width of the heel thereby varying the paths of movement of the knives and therefore the shape of the resultant heel-seat tab formed upon the sole.

8. A heel-seat fitting machine having, in combination, a heel gage comprising a stationary abutment, a slide yieldable under pressure of a heel away from the stationary abutment, said slide being constructed and arranged to force the heel against said abutment to position the heel lengthwise and widthwise in the heel gage, and an abutment movable into engagement with the rear end of the positioned heel, a back gage for positioning a shoe, and mechanism for connecting said back gage to said movable abutment to position the back gage in accordance with the length of the heel in the heel gage.

9. A heel-seat fitting machine having, in combination, a heel gage comprising a stationary abutment, a slide movable toward and away from said abutment, a spring for constantly urging said slide forward toward the abutment, a stop for limiting forward movement of the slide, said slide being constructed and arranged to position the heel widthwise and lengthwise as it forces the breast of the heel against the stationary abutment, and an abutment movable into engagement with the rear end of the heel, a back gage for positioning the shoe lengthwise, and mechanism for connecting the back gage to the movable abutment to position the back gage in accordance with the length of the heel in the heel gage.

GEORGE HAZELTON.
